AUTOMATIC GAIN CONTROL

Lowell E. Norton, Collingswood, N. J., assignor to
 Radio Corporation of America, a corporation of
 Delaware

Application January 28, 1942, Serial No. 428,538

9 Claims. (Cl. 250—20)

1

My invention relates to automatic gain control circuits and particularly to gain control circuits containing no long time constant filter. The invention is especially adapted for use in systems such as the rotating radio beam system described in Luck Patent 2,208,376, issued July 16, 1940, wherein it is desired to remove certain low frequency variations of the order of from 1 to 6 cycles per second, for example, and to remove, also, comparatively high frequency variations which may occur at various random frequencies lying between 40 cycles per second and 100 cycles per second for instance.

In the system described in the above-mentioned Luck patent, an antenna figure-of-eight radiation pattern is rotated at the rate of 60 rotations per second, in one particular example, and the pattern is provided with a reference mark whereby an airplane may determine its position by means of a suitable receiver carried thereby. In this particular system the metal propellers of the airplane introduced a modulation at the receiver having a frequency differing only a few cycles from the 60 cycle frequency introduced by the rotating antenna pattern. Thus there results a modulation component equal to this difference frequency and the cathode ray pattern on the receiver tube tends to "bounce" at this low frequency rate.

It is an object of the present invention to provide an improved automatic gain control circuit for avoiding the above-described undesirable effects in a rotating radio beacon.

A further object of the invention is to provide an improved automatic gain control circuit which removes both low frequency and comparatively high frequency undesired signal variations.

A still further object of the invention is to provide an improved means for and method of developing an automatic gain control voltage.

In one of the preferred embodiments of the invention the signal having the undesired amplitude variation is detected and applied to a clipping circuit which clips at a level that varies with the value of the instantaneous amplitude as determined by the undesired modulation. This may be accomplished by means of a triode having a grounded grid which, together with a resistor-capacitor circuit, is so connected to the detector that the half-wave pulses in its output periodically cause a flow of grid current during which period the condenser receives a charge, and at the end of which the condenser partially discharges. During the flow of grid current the half-wave pulses are clipped off at a certain level. The flat-

2

topped pulses thus obtained may be passed through a filter having a fast time constant to obtain the desired gain control voltage since the filter need hold a charge only for the comparatively short time between successive flat-topped pulses rather than for the time between the peaks of rectified sine waves as would be the case in the usual gain control circuit.

The invention will be better understood from the following description taken in connection with the accompanying drawing in which

Figure 1 is a circuit diagram of one embodiment of the invention,

Figures 2a to 2d are curves which are referred to in explaining the invention,

Figure 3 is a circuit diagram of another embodiment of the invention,

Figure 4 is a series of curves which are referred to in explaining the invention.

Like parts in the several figures are indicated by similar reference characters.

In Fig. 1, one embodiment of the invention is shown applied to the receiver of a rotating beacon system. The receiver, the front end of which is indicated at 9, includes a vacuum tube 10, which may be of the pentode type for amplifying the received signal and supplying it through a conductor 11 to a cathode ray tube indicator circuit (not shown) and through a transformer 12 to my improved automatic gain control circuit. The latter circuit includes a detector comprising diodes 13 and 14 and a load or output resistor 16 across which appears the voltage e (Fig. 2a).

A vacuum tube 17 having a plate 18, a control grid 19 and a cathode 21 is connected across the output resistor 16, the plate 18 preferably being connected through a resistor 22 to the cathode or positive end of resistor 16, and the cathode 21 being connected through a conductor 23 to the plate or negative end of resistor 16. The grid 19 is grounded.

A condenser 24 is connected between the plate 18 and grid 19 and a resistor 26 is connected between the grid 19 and the cathode 21. The capacity of the condenser preferably is small enough to make its impedance at 60 cycles per second large compared with that of the grid-cathode impedance of tube 17 and the resistor 26 in parallel.

The automatic gain control voltage may be obtained at the cathode 21 and applied to a grid of the amplifier tube 10 through a conductor 27 and through a comparatively short time constant filter comprising a series resistor 28 and a shunt condenser 29. In this case the voltage e_1 appear-

ing across resistor 26 is utilized (after filtering by filter 28-29) as the gain control voltage.

The operation will be described with reference to Figs. 2a and 2b which show the voltages e and e_1 , respectively. As a half sine wave pulse of the voltage e increases in amplitude from its zero value, the current flow through the resistor 26 increases correspondingly up to the point where the grid 19 goes positive with respect to the cathode 21 to cause a flow of grid current. It may aid in understanding the operation to note that the series connected elements 22, 24 and 26 may be looked upon as a voltage divider connected across the load resistor 16.

As soon as the grid 19 goes positive, this point being indicated by the broken line 31 in Fig. 2a, the current flow through resistor 26 becomes substantially constant to produce the flat-topped portion of a pulse of voltage e_1 . This current flow remains constant until the half-wave pulse of voltage e decreases to a value where the grid 19 is no longer positive with respect to the cathode 21 and the flow of grid current ceases. The condenser 24 meanwhile has been charged by the flow of grid current, and as the applied voltage e decreases, condenser 24 begins to discharge through the circuit 22, 16, 26.

Since the current flow through resistor 26 is reversed during this short discharge time, the cathode end of resistor 26 goes positive momentarily with respect to ground. The gain control voltage applied to the grid of tube 16, however, is always negative with respect to ground because of the smoothing action of the filter 28-29. This is indicated by the dotted line portion x of Fig. 2b.

When voltage e drops to or close to zero, the cathode 21 will be at the same or nearly the same potential as the upper end of resistor 22 and, therefore, will be positive with respect to the grid 19 as a result of the charge on condenser 24 whereby the tube 17 is biased to cut-off. Now, when the voltage starts to rise again on the next pulse, the tube 17 is still cut-off so that there is no voltage drop in resistor 22 due to plate current flow. Consequently, the potential on condenser 24 never falls to a value as low as it would otherwise, since at plate current cut-off of tube 17 the potential across condenser 24 and resistor 26 in series is increased by the value of the potential across resistor 22 at a time just before plate current cut-off occurs.

As the voltage e increases further in amplitude during this second half-wave pulse, the previously described action is repeated, but the clipping level (or point at which grid current starts to flow) is proportional to the amplitude of the preceding half-wave pulse of voltage e . Specifically, the charge on condenser 24 is proportional to the charging voltage e , and the resulting voltage across condenser 24 opposes the applied voltage e . As soon as the rising voltage e becomes greater than the condenser voltage, then, and only then, does current start to flow through the circuit 24-26 so that the grid 19 goes positive with respect to cathode 21. It is evident that the smaller the amplitude of a pulse of voltage e , the smaller the voltage on condenser 24 during the next following pulse, and the less rise there is in the voltage of the said next pulse when the grid current starts to flow, and also with smaller values of e , the anode-cathode potential of tube 17 is reduced with a corresponding lowering of grid-cathode resistance so that clipping starts at a lower value.

Thus the amplitudes of the flat pulses e_1 in Fig. 2b are proportional to the amplitudes of the pulses e in Fig. 2a whereby any undesired amplitude variations (either fast or slow) of pulses e may be substantially eliminated.

For some applications of the invention the resistor 22 may be omitted whereby the voltage e_1 will have a wave shape such as indicated in Fig. 2d. It will be apparent that the use of resistor 22 will result in a gain control output that will require a minimum amount of filtering.

The plate-cathode voltage e_2 may be utilized for gain control in place of voltage e , if desired. In that case the ground connection is removed from the grid 19 and the plate 18 is grounded instead. If the time constant of condenser 24 and resistor 26 is fast, the voltage e_2 will have the wave shape shown in Fig. 2c; if the time constant is long the wave shape of voltage e_2 will more closely resemble that of voltage e_1 shown in Fig. 2b.

In the embodiment of Fig. 3, a multivibrator 40 is utilized rather than the grounded grid triode of Fig. 1. The detector output e is applied to the plates of multivibrator tubes 41 and 42 through their plate resistors 43 and 44. The multivibrator preferably is symmetrical so that it produces rectangular pulses of the same width at the plates of tubes 41 and 42 as shown in Fig. 4 at a and b , respectively. These pulses will have an amplitude that is proportional to the applied plate voltage e . They are combined by passing them through diodes 46 and 47 and through a common resistor 48 whereby the signal shown at c in Fig. 4 is supplied over the conductor 27 to the filter 28-29. It will be apparent that, as in the case of the circuit shown in Fig. 1, very low frequencies can be substantially eliminated even though the filter 28-29 has a fairly fast time constant. In some uses the filter 28-29, in either Fig. 1 or Fig. 3, may be omitted, particularly since there is some filtering due to tube capacity as indicated at C_g in Fig. 1, for example.

From the foregoing, it will be apparent that I have provided an improved gain control system that is effective to reduce or eliminate very slow signal variations without employing any filter having a slow time constant. Thus the system is capable of removing rapid signal variations as well as the slow ones.

I claim as my invention:

1. In combination, an amplifier for amplifying a signal having an undesired modulation thereon, a rectifier coupled to said amplifier to produce a rectified output signal comprising voltage pulses that have amplitudes determined by said modulation, means for clipping said pulses at a voltage level which varies in accordance with variations in the amplitudes of said pulses, and means for applying said clipped pulses in negative feedback relation to said amplifier for controlling its gain.

2. The invention according to claim 1 wherein said clipped pulses are applied to said amplifier through a filter having a time constant that is fast with respect to the period of the undesired modulation.

3. In combination, an amplifier for amplifying a signal having an undesired modulation thereon, a rectifier having a load resistor coupled to said amplifier to supply thereto a rectified output signal comprising voltage pulses that have amplitudes determined by said modulation, a vacuum tube having a cathode, a plate and a grounded grid, said plate and cathode being connected to the positive and negative ends of said load re-

sistor, respectively, a condenser connected between said plate and grid, a resistor connected between said grid and cathode, and means for applying the potential appearing on said cathode to said amplifier for automatic gain control.

4. The invention according to claim 3 wherein the connection from said plate to the positive end of said load resistor includes a resistor.

5. In combination, an amplifier for amplifying a signal having an undesired modulation thereon, a rectifier having a load resistor coupled to said amplifier to supply thereto a rectified output signal comprising voltage pulses that have amplitudes determined by said modulation, a multivibrator comprising two vacuum tubes each having a plate connected through its plate resistor to the positive end of said load resistor and each having a cathode connected to the other end of said load resistor, means for combining the rectangular voltage pulses appearing at said plates, and means for applying said combined pulses to said amplifier for automatic gain control.

6. In combination, an amplifier for amplifying a signal having an undesired modulation thereon, a rectifier having a load resistor coupled to said amplifier to supply thereto a rectified output signal comprising voltage pulses that have amplitudes determined by said modulation, a multivibrator comprising two vacuum tubes each having a plate connected through its plate re-

30 sistor to the positive end of said load resistor and each having a cathode connected to the other end of said load resistor, means for rectifying and combining the rectangular voltage pulses appearing at said plates, and means for applying said combined pulses to said amplifier for automatic gain control.

7. The invention according to claim 6 wherein said multivibrator is substantially symmetrical whereby the negative and positive pulses are of substantially the same width.

15 8. In combination, an amplifier for amplifying a signal having an undesired modulation thereon, a rectifier coupled to said amplifier to produce a rectified output signal comprising voltage pulses that have amplitudes determined by said modulation, means for converting said pulses into flat-topped pulses having peak values at a voltage level which varies in accordance with variations in the amplitudes of said pulses, and means for applying said flat-topped pulses in negative feedback relation to said amplifier for controlling its gain.

20 25 9. The invention according to claim 8 wherein said flat-topped pulses are applied to said amplifier through a filter having a time constant that is fast with respect to the period of the undesired modulation.
